VALVE FOR MOTOR VEHICLE SUCTION LINES

Erwin C. Horton, Hamburg, N. Y., assignor to
Trico Products Corporation, Buffalo, N. Y.

Application November 6, 1933, Serial No. 696,876

4 Claims. (Cl. 137—139)

This invention relates to an air valve for motor vehicle accessory systems and is particularly adapted for control valves for suction operated accessories, such as air horns and signals.

5 It has heretofore been proposed to provide a valve in the suction line between the accessory and a source of low pressure, such as the intake manifold of the motor vehicle combustion engine, wherein the valve is held to its seat by a fluid pressure differential in which the low pressure acting on the under side of the valve is in communication with the manifold. Such low pressure varies according to the position of the engine throttle and when the suction is high great 10 effort and energy is required to lift or crack the valve from its seat and therefore more powerful means are necessitated to open the valve.

The present invention has for its object to provide a valve construction in which the valve is readily lifted from its seat with a minimum effort.

One embodiment of the invention is illustrated in the accompanying drawing wherein:

Fig. 1 is a diagrammatic view illustrating an accessory system for a motor vehicle utilizing the present air valve;

Fig. 2 is a view of the control unit for the horn system, portions being in section to more clearly disclose the invention;

30 Fig. 3 is a detail sectional view illustrating the operation of the control valve; and

Fig. 4 is a detailed plan view of the valve actuator cage.

Referring more particularly to Fig. 1 wherein 35 a horn system is depicted by way of illustration, the numeral 1 designates the intake manifold of the internal combustion engine 2, 3 the air horns or signals, 4 the electro-magnetic air control valve generally, and 5 the horn button located on the 40 steering wheel 6 and connected in circuit with the control 4 and a source of energy, such as the battery 7, so that when the circuit is closed by means of the push button 5 the electro-magnetic control is energized to open the air signals to the 45 intake manifold whereby the low pressure maintaining therein will function to sound the desired signal. An electric signal 8 may be provided for being automatically connected into the button circuit by an automatic pressure responsive connector 9 when the suction in the intake manifold is insufficient to actuate the air horns, such connector being of any approved type and therefore not illustrated herein in detail as it forms no part of the present invention.

55 Referring more particularly to the remaining

figures of the drawing, the control unit comprises a casing 10 having a valve chamber 11 opening through a valve seat 12 into a low pressure passage 13 which latter in turn is connected by a conduit 14 to the intake manifold 1. A valve 15 normally engages the seat 12 and is held thereon by the low pressure in passage 13 and the high pressure in chamber 11 which latter is connected by one or more communicating passages 16 to the air signals 3.

The valve is disengaged from its seat by an actuator 17 which may be in the form of a core or armature for the solenoid or electro-magnet generally indicated at 18, the latter being connected in circuit with the push button 5. When 15 the solenoid or electro-magnet is deenergized the core 17 is projected as by means of a spring 19 so that the valve may find ready and proper engagement with its seat. When the solenoid is energized the valve will be lifted from its seat 20 so as to establish communication between passage 13 and chamber 11 and thus actuate the accessory.

In order to permit the core 17 to gain sufficient momentum to lift the valve from its seat, the 25 valve is connected to the core by a play connection in the form of a cage having the confining fingers 20, 21, and 22. These fingers freely receive the valve therebetween and have shoulders 23, 24, and 25 overhanging the marginal edge of 30 the valve and in spaced relation thereto so that during the initial movement of the core the fingers will have a preliminary idle movement free and independent of the valve before their shoulders contact the latter. This permits the core 35 to gain sufficient momentum so that when the finger shoulders contact with the valve sufficient force is present to quickly crack the valve off its seat. These valve engaging fingers may be readily formed by a stamping out operation, with the 40 fingers radiating from a central plate 26 which has an aperture 27 to receive a mounting extension 28 on the core.

To facilitate the lifting of the valve from its seat means are provided to effect an uneven 45 lifting of the valve so that the valve will be cracked from its seat at one side before the entire valve is lifted out of engagement with the seat. Such means according to the present disclosure is embodied in the valve engaging shoulders 23, 24, and 25 and their disposition in different planes so that the lowermost shoulder 23 will initially engage the valve and tilt the same on its seat followed by a subsequent engagement by the shoulders 24, there being two such 50 55

shoulders disposed at diametrically disposed points, and lastly by the shoulder 25 which effects a complete separation of the valve from its seat.

5 Such offsetting of the shoulders is diagrammatically illustrated in Fig. 4 wherein the valve cage is opened up in plan view, the extremities of the fingers 20, 21, and 22 being upset along the outer dotted lines at relatively varying distances, 10 as indicated by the broken circles, whereby the shoulders are offset in such relation so that when the fingers are further upset along the inner dotted lines the shoulders 24 will lie substantially in the same plane, with the shoulders 23 15 and 25 disposed above and below such plane of the shoulders 24.

It will thus be observed that, by the initial cracking of the valve from its seat at one side thereof, the opening of the valve is greatly facilitated and expedited with the smallest amount of effort so that a prompt response of the air signal will be obtained with the least expense of energy.

What is claimed is:

1. A control for motor vehicle accessories comprising a valve seat, a valve disc engaging the seat, and an electro-magnetic valve actuator having a play connection with the valve for forcing the valve from its seat, said connection including shoulder portions in different transverse 25 planes for engaging and supporting the margin of the valve at an incline to its seat whereby to initially break the fluid seal by tilting the valve upon its seat during a valve opening movement.

2. A control for motor vehicle accessories comprising a valve seat, a valve engaging the seat, and a valve actuator normally free of the valve and embodying valve lifting fingers overhanging the margin of the valve for forcing the latter 5 from its seat, said fingers being of varying lengths so as to tilt the valve initially on its seat when lifting the valve from its seat.

3. A control for motor vehicle fluid accessories comprising a valve seat, a valve engaging the 10 seat and having a peripheral margin, and an actuator for the valve having a cage freely embracing the peripheral margin of the valve with two pairs of opposed shoulders engaging beyond the peripheral margin to force the valve from its 15 seat, the shoulders of one pair being relatively off-set to opposite sides of the plane including the companion pair of shoulders whereby one of said off-set shoulders will initially engage the peripheral margin to tilt the valve prior to engagement of such margin by the remaining shoulders.

4. A control for motor vehicle accessories, comprising a valve seat, a valve member engaging the seat, and a valve actuating member normally 25 free of the valve, one of said members embodying lifting finger portions overhanging the margin of the other of said members for forcing the valve member from its seat, said finger portions being of varying lengths so as to tilt the valve 30 member initially on its seat when lifting said valve member from its seat.
